UNITED STATES PATENT OFFICE.

C. AXEL BACKSTROM, OF TRENTON, NEW JERSEY, ASSIGNOR TO THE BACKSTROM CENTRIFUGAL SEPARATOR COMPANY, OF NEW JERSEY.

CENTRIFUGAL LIQUID-SEPARATOR.

SPECIFICATION forming part of Letters Patent No. 368,046, dated August 9, 1887.

Application filed January 15, 1887. Serial No. 224,464. (No model.)

To all whom it may concern:

Be it known that I, C. AXEL BACKSTROM, a citizen of the United States, residing at Trenton, in the county of Mercer, State of New Jersey, have invented certain new and useful Improvements in Centrifugal Liquid-Separators, of which the following is a specification, reference being had therein to the accompanying drawings.

1c This invention has relation to centrifugal machines of that class which are employed for separating liquids into their constituent elements when the latter are of different specific gravities.

15 Among the objects of the invention is the provision of a centrifugal machine which is adapted to be operated by hand-power, or power equal thereto, to separate a practicable quantity of liquid into its constituents.

20 Other objects and advantages of the invention will appear in the following description, and the novel features thereof will be particularly pointed out in the claims.

Referring to the drawings, Figure 1 is a perspective, and Fig. 2 is a substantially vertical section, of a centrifugal machine embodying my invention. Fig. 3 is a partial horizontal section on the line X of the separating bowl or chamber. Fig. 4 is a side elevation of the 30 lower portion of the spindle.

Like letters indicate like parts in all the figures of the drawings.

Although I herein describe my invention as applied in use to the separation of cream from milk, I do not limit said invention to any particular use. Among the requisites of a hand separating-machine of the class described are mechanical devices for rotating the bowl which shall possess a minimum frictional contact 40 with each other, means for supplying the milk in a uniform quantity regardless of the depth of milk in the supply-tank, a uniformity in the quantity of milk passing through the bowl during the process of separation, and a bowl 45 of such a character as to subject the milk passing therethrough to the separating process for a definite period. These requisites being met, the machine produced will be capable of being operated by hand, and its size, weight, and 50 cost of manufacture will be such as to place

the machine within the reach of individual dairymen as universally as is the churn.

Referring to the drawings, A represents a standard mounted or formed on a suitable base, A', and having bearings A², A³, A⁴, and A⁵ for the operative parts of the machine. The bearing A⁵ is for the hand-wheel B, which is circumferentially grooved for the operation of the belt B', which is received by a pulley, B², mounted upon the counter-shaft C, which is also provided with a fly-wheel, C', at one end and the master miter-gear C² at the other end.

When operated by power other than hand, the belt B' extends from the pulley B² to the 65 source of power, the hand-wheel remaining idle, or, if desired, being removed.

In the bearing A², which is concentric, is arranged a step, D, which is centrally bored, as at D', and adapted at its upper end to receive a conical convex-ended pin, E. The step D is exteriorly screw-threaded, as at D², for the reception of an adjusting-nut, F, which has formed as a part thereof an oil-cup, F'. Upon the step and encircling the same is a 70 sleeve pulley or gear, G, the teeth G' of which are adapted to mesh with the master-gear C². In other words, the gear G has its hub extended to fit upon the step and is interiorly 75 grooved in spiral form, as at G², the spiral rising in a direction opposite to the designed rotation of the gear, in order that oil within the cup F' shall be carried upwardly within the sleeve or hub to lubricate the same. The upper end of the sleeve is provided with 80 a depending conical removable pin, E', having a convex end similar to and arranged to bear upon the pin E in the step, whereby the pulley, spindle, and bowl are hung or supported upon the pin E, the two pins forming 85 the principal bearing of the parts. The lower end of the spindle H is transversely slotted, as at H', (see Fig. 4,) and in the upper end of the gear or pulley hub or sleeve is a transverse 90 rod, H², which passes through the slot H' of the spindle, whereby the latter is removably connected with the gear or pulley, so that these parts may be separated by lifting the spindle vertically from the pulley, and yet when in 95 connection any rotation of the pulley causes a 100

like movement in the spindle and in the drum mounted theron. Any suitable material may be employed for the pins E E' —as, for example, highly-tempered steel.

5 The spindle H is maintained in the bearing A' by the use of the well-known rubber or other elastic ring, I . The collar I' is bored larger than the spindle, in order to permit of the latter finding its own center during its rotation. The bearing A' is flanged, as at A'' , for the reception of the cream and milk receiving and discharging vessel J , which is by an annular upwardly-inclined flange divided into two annular chambers, J' J'' , each having a discharge-pipe, J' J'' , respectively. This vessel, when made of sheet metal, may be provided with strengthening-brackets J^3 , extending from its depending flange or annular collar J'' to and along the bottom of the vessel. The inner wall, J' , of the vessel encircles the bowl-spindle. The bowl K is in this instance provided with vertical blades K' K'' , all except the latter being provided with a port, K^3 , the port of one blade being at its lower outer corner and the port of the next succeeding blade being at its upper outer corner. Along the edge of the imperforate blade K^3 there is arranged a cream groove, guide, or trough, L , which terminates at a short distance from the top of the blade, as at L' , Fig. 1. The bowl K is in this instance provided with a depending neck, K^3 , and the inner edges of the blades terminate a little outside of the inner vertical wall of the said neck. In the bottom of the bowl is a discharge-port, K^4 , for the milk, which is conducted thereto by a pipe, K^5 , extending along the wall of the neck, the bottom of the bowl, and to the vertical wall of the latter.

A discharge-port, K^6 , having a screw-threaded tube seated therein, is formed in the neck of the vessel for the delivery therethrough of cream into the chamber J' of the vessel J . A supply-vessel, M , is mounted upon the spindle, as shown, and has a delivery-pipe, M' , projecting radially toward the vertical wall of the bowl. By reference to Fig. 3 it will be seen that the supply-pipe M' is arranged at one side of the imperforate blade K^3 , while the discharge-pipe K^5 is arranged at an opposite side thereof.

N represents a supply-tank in which the milk or other liquid to be separated is stored, and from which it is conducted into the supply-vessel M of the bowl by means of an adjustable siphon, the longer leg, O , of which is provided with a cock or valve, P . The longer arm, O , of the siphon passes through the bottom of the tank, while the shorter arm, O' , thereof terminates a distance from the bottom and is supported within the can or tank and above the bottom by a bracket, O^3 .

O^3 represents a U-shaped pipe adapted to fit and slide within the longer and shorter arms of the siphon, and constitutes the bend of the siphon. Now, disregarding the faucet or cock P , or considering the same to be open,

and supposing the upper surface of the milk within the tank N to be at the line X , there is of course greater pressure at the point where the milk enters the shorter arm of the siphon than there would be if the upper surface of the milk were at the line Y . Now, it is well known that in order to cause a flow of liquid through the ordinary siphon suction must be supplied at the end of the longer arm. In my construction, however, this necessity is obviated, for by raising the sliding U-shaped pipe O^3 to or above the position shown in dotted lines the increased pressure of the liquid at that depth is utilized to cause a flow through the siphon, after which the pipe is lowered to the position shown in full lines, when the pressure remains the same as though the liquid in the vessel were no deeper than with the upper surface at the line Y . In this manner a continuous uniform pressure of supply is maintained. The quantity delivered from the tank into the receiving-vessel of the bowl is controlled by the cock P , so that no more liquid is delivered into the bowl than can be properly separated thereby and delivered therefrom. By extending the height of the bowl in proportion to its diameter, and by arranging the ports of the vertical blades as described, and by providing the cream groove or guide L , I am able to subject a given quantity of milk or other liquid to the separating operation for a desired period.

The service performed by the cream-groove is to receive the cream as fast as (or, more properly speaking, in the locality where) it is first separated in the bowl. In the operation of this bowl the milk, being delivered from the vessel M through the pipe M' , proceeds in a current around and up and down along the inner wall of the bowl, while the cream, being of lighter specific gravity, collects in an annular body near the center of the bowl. Now, by reason of the relative height of the bowl, the cream naturally assumes about the position indicated by the diagonal dotted line Z —that is to say, the annular body of cream within the bowl is wider at its top than at lower portions thereof; hence it is advisable to provide a guide or way of escape or delivery from the bowl which shall be free from interference by the wider annular body of milk in the lower part of the bowl and above its neck, so that by the action of gravity alone the cream may be delivered from the bowl through the port J^6 and into the chamber J , and out of said chamber into any suitable receptacle, J^3 . The skimmed milk is delivered by the pipe K^5 through the port K^4 , into the chamber J'' of the vessel J , and from thence into any suitable receptacle by means of the pipe J' .

The purpose of the cock P , as before stated, is to control—that is, to let in and cut off—the supply of liquid from the tank. Now, without the siphon, which is to control the pressure regardless of the depth of liquid in the tank, a partial opening of the cock to regulate the quantity delivered from the tank would not

answer the purpose in view, because after a time the pressure of the liquid in the tank becomes lessened; at which time it would be necessary to open the cock still farther.

5 A uniformity of supply to the bowl of the machine being essential to a perfect operation, there is a material co-operation between said bowl and the tank provided with the siphon, and still the tank provided with the siphon 10 may be employed with bowls differing in construction from that herein shown and described. So, also, other novel features of my invention may be embodied in centrifugal machines differing in other respects from that herein shown and described. I therefore do not limit my invention to a use of all the novel features thereof in one machine of the class 15 specified.

What I claim is—

- 20 1. In a centrifugal machine, a gear or pulley having one end of its hub conically bored and provided with a removable convex pin and the remaining portion of its hub fitted to embrace and operate upon a step having a similar pin, substantially as specified.
- 25 2. In a centrifugal machine, a step screw-threaded for adjustment and provided with an adjusting-nut made in the form of an oil-bowl, in combination with an interiorly spirally-grooved pulley bored to fit the step, substantially as specified.
- 30 3. In a centrifugal machine, a pulley or gear

provided with an internal spiral oil-groove, the spiral rising in the direction opposite to the rotation of the pulley or gear, in combination with an oil bowl or reservoir whereby the oil is carried upward along the bearing within the pulley by the rotation thereof, substantially as specified. 35

4. The combination, with the separating-bowl of a centrifugal machine, of a tank mounted above the bowl and provided with a short and long arm of an adjustable siphon, the latter supported within and above the bottom of the tank, a movable siphon-bend, and a cock arranged in the longer arm of the siphon, substantially as specified. 40

5. The combination of the step D, pin E, gear or pulley G, having pin E' and rod H', and the spindle H, slotted as at H', substantially as specified. 50

6. The combination, with the bowl K, having discharge-ports K¹ K⁶, and the vertical blades K', having ports K³, of the imperforate blade K², the cream guide or groove L, and the discharge-pipe K⁵, substantially as specified. 55

In testimony whereof I affix my signature in presence of two witnesses.
